MEANS FOR FASTENING TIE-PLATES UPON CROSSTIES

Fred A. Preston, Lake Forest, Ill., assignor, by mesne assignments, to Poor & Company, Chicago, Ill., a corporation of Delaware

Application May 22, 1944, Serial No. 536,785

1 Claim. (Cl. 238—314)

This invention relates to improvements in means for fastening railway tie-plates upon railway cross-ties.

Generally speaking, the object of the invention is to provide a simple, practical, inexpensive means for the purpose stated which may readily be applied to a cross-tie and a tie plate and which, when operatively applied, has spring energy stored therein so that it acts constantly to hold the tie-plate firmly seated upon the tie; i. e., both initially and as any wearing or sinking of the tie-plate into the tie occurs.

With the foregoing and other objects in view, which will become more fully apparent as the nature of the invention is better understood, the same consists in a tie-plate fastening means embodying the novel features of construction, combination and arrangement of parts as will be hereinafter more fully described, illustrated in the accompanying drawing and defined in the appended claim.

In the accompanying drawing, wherein like characters of reference denote corresponding parts in the different views:

Figure 1 is a side elevation of a portion of a cross-tie, showing a tie-plate seated thereon and fastened thereto by means constructed and operating in accordance with the invention.

Figure 2 is an end view of the structure shown in Figs. 1 and 3.

Figure 3 is a top plan view of the structure shown in Fig. 1; and

Figure 4 is a sectional view on an enlarged scale illustrating a detail of the structure.

Referring to the drawing in detail, A designates a portion of a cross-tie, B designates a tie-plate seated upon the top of the cross-tie A, C designates a portion of a rail seated upon the tie-plate B, and D designates, generally, a means, constructed and operating in accordance with the invention, for fastening the tie-plate B upon the cross-tie A.

The tie-plate B may be of any standard or preferred design and spikes, clips or any other suitable means may be provided to maintain the rail C seated thereon or in operative relationship thereto.

In association with any given tie-plate B only a single fastening means D may be employed at either end thereof, or two fastening means D may be employed, one at each end thereof. In any event, any given fastening means D comprises a yoke 10 and a cooperating strap 11, the yoke being of U-shape and preferably of one-piece construction and including a horizontally dis-

posed bottom portion 12 and a pair of vertically disposed arms 13, 13 rising from the ends thereof, and the strap 11 being simply an elongated element provided at its ends with slots 14, 14 to receive the free upper end portions of the arms 13, 13, respectively.

The arms 13, 13 are spaced apart a distance corresponding substantially to the width of the cross-tie A and are of lengths somewhat greater than the height of the cross-tie. Accordingly, when the yoke 10 is operatively applied to the cross-tie in the manner shown in the drawing, with its horizontally disposed bottom portion 12 underlying the tie and engaged with the bottom face thereof and with its arms 13, 13 extending upwardly at opposite sides of the tie, respectively, the tie is snugly embraced by said yoke and the arms 13, 13 extend above the top thereof.

Both the yoke 10 and the strap 11 are formed from spring steel of suitable cross sectional size and shape. Moreover, the outer edges of the free upper end portions of the arms 13, 13 are provided with downwardly facing ratchet teeth 15 and the walls defining the outer ends of the slots 14, 14 are inclined downwardly and outwardly to provide at the upper, outer corner of each slot 14 an upwardly facing tooth 16 for cooperation with the teeth 15 of the related arm 13. In addition, the normal spaced apart relationship of the free upper end portions of the arms 13, 13 is such that the distance between the bases of the teeth 15 of the respective arms is at least as great as the distance between the peaks of the respective teeth 16. It is manifest, therefore, that in order for the strap 11 to be moved downwardly over the free upper end portions of the arms 13, 13, it is necessary that said portions of said arms be flexed inwardly to permit the teeth 16 to ride over the teeth 15. It is equally manifest that when the teeth 16 ride over any of the teeth 15, the free upper end portions of the arms 13, 13 will spring outwardly and thereby cause the teeth 15, 16 to cooperate with each other to hold the end portions of the strap 11 against upward movement relative to the arms 13, 13. In short, the described construction provides ratchet connections between the end portions of the strap 11 and the free upper end portions of the arms 13, 13, permitting the end portions of said strap readily to be moved downwardly relative to said arm portions, but preventing their upward movement relative thereto.

The yoke 10 first is applied to the tie A in alignment with an end portion of the tie-plate B and is held temporarily in any suitable manner in

its uppermost position with its bottom portion 12 engaged with the under face of the tie. The strap 11 then is disposed transversely with respect to the tie-plate, across the top thereof, and the free upper end portions of the arms 13, 13 are entered in the slots 14, 14. Then, in any suitable manner and by the employment of any suitable implement, or implements, the ends of the strap 11 are forced downwardly relative to the arms 13, 13, not only until the medial portion of said strap is engaged with the top of the tie plate, but thereafter until the end portions of the strap have been flexed downwardly relative to the medial portion thereof. As the end portions of the strap are flexed downwardly, the teeth 16 cooperate successively with the teeth 15 to maintain said end portions flexed downwardly. Thus, spring energy is stored in the strap and this stored spring energy tends constantly to urge the yoke upwardly and the strap downwardly, with the result that the tie-plate is maintained securely clamped against the tie both initially and as any sinking or wearing of the tie-plate into the tie occurs.

Obviously, the strap 11 may be normally straight or normally bowed. Obviously, too, the free upper end portions of the arms 13, 13, instead of having teeth at their outer edges, may have teeth at their inner edges for cooperation with teeth at the inner ends instead of at the outer ends of the slots 14, 14, which would involve having the upper ends of the arms 13, 13 spaced apart to be sprung outwardly instead of inwardly for engagement in said slots 14, 14. In other words, the arrangement shown with respect to the teeth 15, 16 obviously might readily be reversed. Moreover, the strap and yoke arrangement with respect to the tie obviously might also be reversed if desired by inverting the yoke and disposing the strap beneath the tie instead of across the tie-plate, since the result would be the same in either case. The arrangement shown both in respect to the teeth 15, 16 and the yoke and the strap relative to the tie is preferred, however, as being generally more practical than any of the alternative arrangements mentioned.

While it is not essential that any means be provided to hold the fastening means D against creeping longitudinally with respect to the tie-plate B, or vice versa, the tie-plate may be suitably provided, if desired, at either or both ends thereof with either a transverse depression or with a pair of upstanding ribs 17 as shown providing therebetween a channel to accommodate the strap 11, thus to insure an initial predetermined relationship between said strap and said tie-plate and also to insure maintenance of this relationship.

Obviously each arm 13 might be provided with only a single tooth in lieu of the series of teeth 15 shown for cooperation with either a single tooth or a plurality of teeth at the related end of the related slot 14, or, alternatively, any equivalent of the teeth 15, 16 might be provided in

lieu of said teeth. Moreover, to facilitate insertion of the free end portions of the arms 13, 13 into the slots 14, 14, the toothed edges of said free end portions may be beveled as indicated at 18.

As will be manifest, the fastening means D serves not only to maintain the tie-plate firmly seated upon the tie, and the tie against dropping away from the tie-plate, but also as a clamp-band to hold the tie against splitting and spreading.

Should it be desired at any time to release any given fastening means D, this may readily be done simply by springing the free ends of the arms 13, 13 or in a direction to disengage the teeth 15 from the teeth 16.

Without further description it is thought that the features and advantages of the invention will be readily apparent to those skilled in the art, and it will of course be understood that changes in the form, proportion and minor details of construction may be resorted to, without departing from the spirit of the invention and scope of the appended claim.

I claim:

Means to clamp a tie-plate securely upon a cross-tie comprising a U-shaped yoke including a pair of upright arms disposed at opposite sides of the tie, respectively, and a horizontally disposed portion connecting said arms at their lower ends and extending beneath the tie and seated against the bottom thereof, a strap of spring material engaged with and extending across the top of the tie-plate and having slots in the end portions thereof through which the upper end portions of said yoke arms extend, teeth at the outer sides of the upper end portions of said yoke-arms having downwardly and outwardly inclined outer faces, teeth at the outer ends of the slots in said strap for engagement with the teeth of said yoke arms to hold the end portions of said strap under downward flexure and thus hold the tie plate clamped downwardly against the tie, the normal distance between the outer faces of the upper end portions of said arms being greater than the distance between the outer ends of said slots so that the upper end portions of said arms must be sprung inwardly to permit them to enter said slots, the distance between the lower portions of said arms being substantially equal to the width of the tie so that when the upper portions of said arms are sprung inwardly the said lower portions thereof are drawn into tight engagement with the sides of the tie, the said upper portions of said arms being offset outwardly from their lower portions for fastening cooperation with said strap at points spaced well outwardly from the sides of the tie plate to insure relatively long end portions of said strap extending beyond the sides of the tie plate for downward flexure.

FRED A. PRESTON.
